(57) **CLAIM**

The ornamental design for a table lighter, as shown and described.

DESCRIPTION

FIG. 1 is a front, right, and top perspective view of a table lighter, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a groove.

FIG. 10 is a partial enlarged view of an area labeled 10 in FIG. 1 comprising an ignition switch; and,

FIG. 11 is a partial enlarged view of an area labeled 11 in FIG. 2 comprising a part of a battery cover.

The broken lines consisting of evenly spaced dash lines in the drawing depict portions of the table lighter that form no part of the claimed design; The broken lines consisting of short and long dash lines encircling the enlarged detail views are for annotative purposes that form no part of the claimed design.
